UNITED STATES PATENT OFFICE

2,035,928

ROTARY HOOK FOR SEWING MACHINES

Clarence C. Smith, Chicago, Ill., assignor to Union Special Machine Company, Chicago, Ill., a corporation of Illinois

Application October 5, 1934, Serial No. 747,053

6 Claims. (Cl. 112—256)

The present invention relates to new and useful improvements in a rotary hook for a lock stitch sewing machine and more particularly to a rotary hook construction which affords novel lubricating 5 means for the interengaging parts between the rotary hook and the stationary bobbin casing.

An object of the present invention is to provide a rotary hook wherein means are provided for directing lubricant from a point adjacent the axis 10 of the hook exteriorly of the rear face thereof to the interengaging parts between the rotary hook and the bobbin casing, and wherein said means may be attached to the rotary hook with very little change therein and may be readily removed 15 for cleaning.

A further object of the invention is to provide, in a rotary hook, means for lubricating the interengaging parts between the rotary hook and the stationary bobbin casing wherein a tube leading 20 from a recess at the axis of the rotary hook to an inclined surface on the inner face of the hook rim is adapted to form a conduit through which oil may be caused to flow by centrifugal force to the interengaging parts.

25 The above and other objects of the invention will in part be obvious and will be hereinafter more fully pointed out.

In the accompanying drawing:

30 Figure 1 is a side view in section showing the assembled rotary hook, bobbin, bobbin casing and a portion of the bearing and actuating shaft.

Fig. 2 is a rear view taken along line 2—2 of Fig. 1.

35 The invention relates generally to lubricating means for the interengaging parts between the rotary hook and the stationary bobbin casing.

The rotary hook is fixed to the end of a rotating shaft and the bobbin and the bobbin casing are mounted within and supported by the rotary hook. 40 The bobbin casing is provided with a circumferential rib which engages a groove or raceway in the hook and thus lateral movement between the bobbin casing and the rotary hook is prevented. A portion of the bobbin casing engages a fixed

45 part of the sewing machine in order to prevent rotation of the casing within the rotary hook. Extending longitudinally and centrally of the rotating shaft is a port which is open at the end of the shaft adjacent the hook and which is pref- 50 erably provided with wicking. The shaft terminates short of the inner face of the rotary hook in order to provide a recess at the axis thereof. A sleeve or bushing, in which the shaft rotates, is provided with an opening which registers with

55 an oil hole from which oil may be admitted to

the port in the shaft through a suitable opening therein. Thus the lubricating oil may be fed to the recess formed in the hub of the rotary hook. The hub of the rotary hook is provided with a radial port communicating with the recess there- 5 in. One end of a tube is fitted in this port and the opposite end thereof is disposed within an overhanging part of the hook rim, the surface of which is inclined toward the interengaging parts between the rotary hook and the bobbin casing 10 so that oil passing through the tube by centrifugal force will likewise follow this inclined surface on the hook rim to the interengaging parts. It will be seen that the thread passing between the rotary hook and the bobbin casing will not come 15 in contact with the oil tube and so will not be- come soiled.

Referring more in detail to the accompanying drawing, the invention is shown as applied to a sewing machine having a work support 10 which is provided with a depending bearing bracket in which is mounted a bushing 11. The actuating shaft 12 is mounted within the bushing 11 and carries at the end thereof a rotary hook 13. The actuating shaft 12 may be driven by suitable in- 20 termeshing gears, as shown in the co-pending application of George Sauer, Serial No. 688,512, filed September 7, 1933, and described in detail in the co-pending application of Norman V. Christensen, et al., Serial No. 670,186, filed May 9, 1933. 30 The shaft 12 may also be driven in the manner shown and described in the co-pending applications of George Sauer, Serial Nos. 716,415 and 716,416, filed March 19, 1934. The particular manner in which the rotary hook is driven forms 35 no part of the present invention.

The rotary hook 13 is of the usual cup-shaped construction with portions cut away to form spaced radial webs or spokes 14 which are formed as a part of the hub 15. One side wall of the cup 40 is shaped to provide a hook which is adapted to enter the needle thread loop and carry the same about the bobbin casing 16 which is also cup-shaped and is adapted to receive and support a bobbin 17 therein. The bobbin 17 is held within 45 the bobbin casing by a cover or carrier 18. The bobbin casing 16 is provided with a circumferential rib 19 which fits within a groove or race- 50 way 20 in the rotary hook. The rib 19 and race- way 20 form interengaging parts to prevent lat- eral movement of the bobbin casing within the rotary hook. The bobbin casing is provided with a projecting portion 21 which engages a fixed part of the sewing machine in order to pre- 55 vent the rotation thereof. The rotary hook op-

erates in the usual manner and further description thereof is not considered necessary.

The present invention relates more particularly to a means for lubricating the interengaging parts 5 between the bobbin casing and the rotary hook. When the hub 15 of the rotary hook is placed on the shaft 12 and secured thereto by one or more set screws 22, there is preferably left a space between the end of the shaft and the inner face of 10 the rotary hook, thus forming a recess 23 which is closed at the inner face of the rotary hook by a closure plate 24 in order to provide a closed recess to retain oil therein and prevent it from reaching the inner face of the rotary hook.

15 In the drawing, by way of illustration, the hub 15 is shown as provided with a port 25 which extends radially therethrough and which communicates with the recess 23. One end of an oil tube 26 is mounted in the port 25 in the hub 15. 20 The free end of the tube 26 is bent slightly to underlie an overhanging portion 27 on the hook rim between two spokes. The inner face 28 of the hook rim is inclined and leads to the raceway 20. While only one tube and one port 25 have 25 been shown, it is to be clearly understood that a plurality of the same may be employed if so desired.

The actuating shaft 12 is provided with a central bore 29 which opens into the recess 23 and 30 is preferably filled with wicking. The bushing 11 is provided with an opening 30 which registers with an oil hole 31 in the bearing bracket of the machine. Thus oil may be admitted through the oil hole 31 and the opening 30 in the bushing and 35 it will then pass into the bore 29 through an opening 32 in the shaft 12. The oil will then flow into the recess 23 from which it will be thrown by centrifugal force through the port 25 and tube 26 to the inclined surface 28 from which it 40 will reach the raceway 20 so that, as the hook rotates, the interengaging parts between the rotary hook and the bobbin casing, that is, the raceway 20 and the rib 19, will be efficiently lubricated without any danger of soiling the thread. 45 It is to be noted that the hook may be easily cleaned so that the danger of clogging of the oil tube is prevented.

From the foregoing description it will be seen that the tube 26 may be easily connected to the 50 hub of the rotary hook without making any changes in the spokes of the hook and that it may be removed conveniently for cleaning.

It is to be clearly understood that minor 55 changes in the details of construction and arrangement of parts may be made without departing from the scope of the invention as set forth in the appended claims.

Having thus fully described my invention, what I claim as new and desire to secure by Letters 60 Patent, is:—

1. In a sewing machine, the combination of a rotary hook, a stationary bobbin casing supported therein, said hook and casing having interengaging parts to prevent relative lateral movement 65 therebetween, and detachable means located ex-

teriorly of the rear face of said hook and rotatable therewith and having a conduit therethrough for directing lubricant from a point adjacent the axis of the hook to the inner face of the hook rim whereby to lubricate said interengaging parts. 5

2. In a sewing machine, the combination of a rotary hook having a hub, a rim portion and spaced radial webs connecting said hub and rim portion, of a stationary bobbin casing supported by said hook, said hook and casing having interengaging parts to prevent relative lateral movement therebetween, and means connected to said hub exteriorly of said webs for directing lubricant to the inner face of said rim between two of said webs whereby to lubricate said interengaging parts. 10 15

3. In a sewing machine, the combination of a rotary hook having a hub, a rim portion and a connecting web portion, of a stationary bobbin casing supported therein, said hook and casing 20 having interengaging parts to prevent relative lateral movement therebetween, and means for directing lubricant from a supply adjacent the axis of the hook to said interengaging parts and including a tube disposed exteriorly of said web 25 portion and leading from said supply to a point adjacent said interengaging parts.

4. In a sewing machine, the combination of a rotary hook, a stationary bobbin casing supported 30 therein, said hook and casing having interengaging parts to prevent relative lateral movement therebetween, said hook having a recess at the axis thereof, and means for directing lubricant from said recess to said interengaging parts and including a tube mounted on the hub 35 of the hook communicating with said recess.

5. In a sewing machine, the combination of a rotary hook having a hub, a rim portion and spaced radial webs connecting said hub and rim portion, of a stationary bobbin casing supported 40 within said rim portion, said hook and casing having interengaging parts to prevent relative lateral movement therebetween, said rim having an inclined surface between two of said webs, and means for directing lubricant from a supply 45 adjacent the axis of said hook to said inclined surface whereby to lubricate said interengaging parts and including a tube mounted in said hub and having the free end thereof adjacent said inclined surface.

6. In a sewing machine, the combination of a rotary hook having a hub, a rim portion and spaced radial webs connecting said hub and said rim portion, of a stationary bobbin casing supported by said hook, said hook and casing having 55 interengaging parts to prevent relative lateral movement therebetween, and means for directing lubricant from a supply in said hub to said interengaging parts and including a tubular member having one end mounted in said hub and having the opposite end thereof bent inwardly 60 to lie adjacent the inner face of said rim portion between two of said webs.
